COIN CONTROL MECHANISM

Frank A. Madden, Salina, Kans.

Original application October 26, 1925, Serial No. 64,735. Divided and this application April 24, 1931. Serial No. 532,431

6 Claims. (Cl. 194—87)

This application is a division of my application filed October 26, 1925, Serial No. 64,735.

This invention relates to the art of coin control mechanism, wherein a coin deposited in a machine will act as a medium for the operation of the machine from a source of power, and wherein a coin once operated upon by the machine to vend a ware cannot be used a second time.

10 An object of my invention is to provide a mechanism for the reception of a coin wherein it becomes a medium for the transmission of power from its source to the operating members of the machine, and in the case of a vending machine, is utilized to transmit power to the operating elements of the machine for the purpose of vending wares equivalent to the coin involved in the particular operation.

An object of my invention is to provide a 20 means for closing the coin slot of such mechanism against the passage of a coin therethrough after the insertion of a previous coin and during the operation of the machine, and as illustrated herewith a vending machine, for the purpose of vending a ware in response to the injection of one coin, and the removal of the closing means upon the completion of a vending operation.

An object of my invention is to provide means 30 for closing a coin slot against passage of a coin therethrough upon the exhaustion of the wares to be vended, and the opening of the slot for the passage of coins when such wares are again available.

For the purpose of illustrating the adaptability 35 of my invention to commercial use in conjunction with a vending machine, I have illustrated the invention as being constructed in conjunction with a drink vending machine, wherein a supply of cups is maintained adapted to be singly separated and discharged to a position wherein they are filled with a drink for dispensing, upon the application of a coin to and within the coin slot, and the application of motive power to operate the machine; in the machine illustrated 40 the source of power is through the manual operation of a crank by the purchaser of the drink. It being prearranged that there are a less number of cups than the corresponding quantity of liquid to fill them, the machine is assumed to 45 be exhausted of wares when the supply of cups is exhausted, and to provide for the preventing of intending purchasers inserting coins into a machine with an inadequate supply of the wares it is supposed to vend, I have provided the slot 50 closing mechanism which is permitted to enter the

coin slot, upon exhaustion of the supply of cups, at a point where a coin which might be intended for insertion in the slot would only enter a portion of its breadth, thus providing the intending purchaser a means of retaining the coin, 60 rather than utilizing the conventional method of dropping the coin in a slot, and then having the machine return the coin by mechanical means.

An object of my invention is to provide a coin 65 control mechanism wherein the slot closing device is normally in contact with the supply of wares to be vended, but to prevent injury to such wares upon their progressive movement attendant upon the vending operation, I have provided that 70 the slot closing mechanism be removed from contact with the wares during such progressive movement, and returned to a contact position upon cessation of such movement, thereby providing means for setting the slot closing mechanism to close the slot immediately upon exhaustion 75 of the wares.

An object of this invention is to positively discharge the coin into the receptacle therefor when it has served its purpose of forming a suitable 80 connection to operate the vending machine to vend wares.

A feature of the invention is the employment 85 of the coin to tension a spring, the force of which serves to knock the coin out of its carrier before the vending mechanism delivers a ware.

Another object is to retain the coin in its operative position until the vending mechanism has been started into operation.

In this invention provision is made whereby 90 the crank may be freely oscillated after any operation of the machine, without again operating the machine unless connection between the crank and the operating mechanism is made by an inserted coin which is displaced from its operative position when the crank passes a certain position, and such coin is then displaced positively by spring actuated means.

A further feature consists in means to bar passage of a coin, except when the hand crank is in 100 initial or normal non-operative position.

Other objects, advantages and features of my invention may appear from the accompanying drawings, the subjoined detailed description and the appended claims.

The accompanying drawings illustrate the invention in a form I at present deem preferable.

Figure 1 is a broken front elevation of a dispensing machine constructed in accordance with this invention, with a filled cup ready for de- 110

livery and the crank returned to position for starting another operation. Broken lines indicate the position of the crank at the coin dislodging instant.

5 Fig. 2 is a broken side elevation of the machine looking from the left in Fig. 1, and showing a fragment of the case. A portion of one side wall of the frame is broken to expose the cup passage; broken lines indicate mechanism outside the other 10 wall.

Fig. 3 is a plan of one of the three cup-feeding disks.

Fig. 4 is an elevation of the rear cup-feeding disk.

15 Fig. 5 is an elevation of one of the front cup-feeding disks.

Fig. 6 is a side elevation looking from the right in Fig. 1.

20 Fig. 7 is a sectional view taken on irregular line 7-7 in Figs. 1 and 8, omitting the pressure liquid pipe and other parts.

Fig. 8 is a plan view of the machine, omitting the filled cup shown in Fig. 1.

25 Fig. 9 is a fragmentary sectional view of the cup dispenser with cups in place, viewed from line 9-9 in Fig. 12.

Fig. 10 is a fragmentary plan view of the crank in a partially operated position, the crank-controlled coin-slot guard in slot closing position, 30 the cup-retracted coin-slot guard retracted by the crank-controlled coin-slot guard from the coin slot and out of engagement with the cup. Dotted lines indicate the position of the cup retracted guard when the cup supply is exhausted.

35 Fig. 11 is a fragmentary front elevation showing the crank in original position, the crank-controlled coin-slot guard, and a fragment of the cup-controlled coin-slot guard; the frame is broken to show the crank cam and the coin carrier; solid lines show the crank at rest and the 40 crank-controlled coin-slot guard withdrawn; broken lines indicate a moved position of the crank as turned, and the crank-controlled coin-slot guard in slot-guarding position.

45 Fig. 12 is a plan view of the cup dispenser.

Fig. 13 is a fragmentary vertical section on lines 13-13 in Figs. 16 and 17. Broken lines indicate the position of the parts the moment before the knock-out tappet is sprung to eject the coin 50 from the coin carrier.

Fig. 14 is an elevation showing the left side of the cup dispenser shown in Fig. 12.

Fig. 15 is a view looking up at the bottom of the cup dispenser mechanism shown in Figs. 12 and 14.

55 Fig. 16 is a fragmentary vertical section on lines 16-16 in Fig. 1.

Fig. 17 is a fragmentary right side elevation of the forward end of the machine; parts are broken away to show interior construction of the coin-control mechanism.

Fig. 18 is a fragmentary elevation of the forward end of the machine looking from the right side of Fig. 17, and from a plane indicated by 60 lines 18-18 in Fig. 7.

65 It will be obvious that the coin-controlled mechanism is per se an invention and may be operated, if desired, separately from any drink dispensing means or cup dispensing means, and 70 in conjunction with any other mechanism, that it may be desired to operate thru a coin-controlled device. For such operation it is only necessary to extend the driven elements to connect with such other mechanism, and thereupon 75 an inserted coin may be used as the medium for

transmitting power thru the driven elements to such connected mechanism.

Hence, the coin-controlled mechanism which is hereinafter described and claimed may be combined with many different kinds of devices, preferably vending machines wherein wares are dispensed presumably in amounts or quantities relative to the value of a coin inserted in the coin slot, and wherein this vending-type of machine is known as the coin-controlled type. In the 80

85 drawings of the present application a coin-controlled drink-vending device is illustrated, designed to vend a drink consisting of two component parts; viz., a syrup and a charge of carbonated water delivered under pressure and mixed with said syrup by the machine at the time of its delivery therefrom into a cup provided for that purpose.

90 By reference to Fig. 1 it will be seen that the main portion of the machine consists of a metal frame having a base member 20 and a top member 21 connected by struts 22 at either side spaced apart and secured to said base and top members by cap screws 23.

95 The base member 20 is provided with a recess 24 which is open at the front side and has a horizontal U-shaped forwardly-open lip 25 upon which the released cup 26, in which the drink is to be vended, is supported to receive the drink mixture.

100 A spout 27, see Fig. 7, is provided to take care of any drip, and a chute 28 located at the bottom of the recess 24 is provided to drop the used cups thru, and leads to a suitable receptacle, not shown.

105 The base member 20 is provided with an extension upwardly of the recess 24 constituting the vertical passage 29 thru which the cups are delivered one at a time from a magazine above to the U-shaped lip 25, by cup dispensing means, hereinafter to be described, when the machine is 110 operated to vend a drink.

115 The manually operated actuating mechanism comprises a hand crank 30 secured to a horizontal shaft 31 that is journaled in a supporting rib 32 at one side of the base member 20 and projects from the rear face thereof, and operates a coin carrier 33 rigidly fixed to the crank shaft 31 by pin 34; the coin carrier 33 is rotatably mounted upon a portion of shaft 35; the shaft 35 is rotatably journaled within the supporting web 36, a part of the rear section of the frame 20, as best shown in Fig. 6.

120 By referring to Fig. 1 it will be seen that I have provided a coin slot opening at 37, in Fig. 2 the coin slot 37 is shown in broken lines, in Fig. 6 it is also shown in broken lines, in Fig. 11 the coin slot 37 is shown partly in section, in Fig. 13 the discharge end of the coin slot 37 is illustrated in section, in Fig. 16 the coin slot 37 is shown in 125 its entirety, and in Fig. 17 it is again shown in broken lines; this coin slot 37 is adapted to receive and conduct a coin of a predetermined denomination to pay for one of the drinks as vended by a drink cup such as the illustrated cup 26 130 to the purchaser.

135 The coin slot 37 conducts a coin to the coin carrier 33 where it assumes the position illustrated in Fig. 16, having come to rest within a slotted portion of the carrier 33 in a position to 140 operate the driven elements of the mechanism by contacting the tappet 38 located between the limbs 40 and 41 of the carrier 33 and keyed to the shaft 35; the carrier 33 is preferably U-shaped and the open space 29 between the limbs 40 and 41 is of 145 150

less width than the coin slot 37; the inside faces of the limbs 40 and 41 have grooves 42 provided to receive the coin and are provided at their lower portions to curve toward each other and form a coin seat 43 upon which the coin will rest when in the position illustrated by the coin 44 in Fig. 16, wherein it bridges the open space between the limbs 40 and 41 of the carrier 33, and upon oscillation of the carrier 33 by the crank 30 the coin will contact the tappet 38 which, being keyed to the recited shaft 35, will thereby actuate the driven elements of the machine.

A coil spring 45, having one end secured to the web 36 and the other end to the carrier 33, is arranged to yieldingly hold the coin carrier 33 against the side of the frame member 20 in a position to receive from the coin slot 37 a coin to bridge the space 39 and operate the tappet 38 to rotate the shaft 35.

The spring 45 returns the carrier 33 with considerable force to its original position where it stops against the frame 20, and there is likelihood of considerable wear at the point of contact, thus mis-aligning the carrier 33 with reference to the coin slot 37, and to provide for proper adjustment against wear at this point I have provided means in the form of adjustable screws 46 in the carrier 33 to contact the frame 20 so that when wear occurs adjustment may be made to re-align the carrier 33 with the coin slot 37.

Upon the rotation of the crank 30 with a coin in proper position in the carrier 33, it will engage the tappet 38 and rotate the shaft 35 in one direction; the shaft 35, as best shown in Fig. 17, extends thru the web 36 a sufficient distance to have secured to it a mitre gear wheel 47, as best shown in Figs. 2, 6, 17 and 18, where it meshes with the gear 48 secured to a vertical shaft 49 which is journaled in shaft bearing frame 50 which is attached to the frame 20; the vertical shaft 49 has further secured to it a gear 51 (see Fig. 18); a horizontal shaft 52 supported by bearings 53 attached to the frame 20 is provided at its opposite ends with gear wheels 54, one of which meshes with the recited gear 51 and the other with a gear wheel 55 secured to a vertical shaft 56 which connects to the cup dispensing apparatus hereinafter to be described.

By reference to Fig. 2 it will be seen that the gear 48 engages a gear 57 mounted on a shaft 58 rotatably supported by the bearing 59 and extending inwardly of the machine a sufficient distance to accommodate a spring 60 and to pass thru an additional bearing 61, and support on its other end the revolvable member 62 to which are secured the springs 63 and 64 which form a master spring eccentrically connected by crank pin 65 to the revolvable member 62 and holding it in a predetermined position; the operation of the tappet 38 by the coin in the carrier 33 is against the resistance of the springs 63 and 64, such resistance affords a friction on the coin that tends to hold the coin in the coin seat 43 during an operation. The coin enters the coin seat 43 from above when the carrier 33 is in starting position, and when the carrier 33 is oscillated it comes to a point where it is inverted and the coin would be drawn out by gravity if it were not for the friction caused by the resistance of the springs 63 and 64 which are given tension by the revolution of the member 62; when the pin 65, by which the springs 63 and 64 are eccentrically connected to the member 62, comes to dead center as the springs swing across the axis of the member 62, the resistance of the springs to the

advance of the tappet 38 under the pressure of the coin in the carrier 33 is so reduced that the friction on the coin would be insufficient to hold the coin in position and it would drop out of the inverted carrier 33, thus leaving no connection between the carrier 33 and the tappet 38, so that operation of the machine would not be carried on.

To overcome this difficulty, the shaft 58 is made in two alined sections connected to each other by a coupling comprising the recited spring 60 which is secured to each of the two sections of the shaft 58, one section of which is secured to the recited member 62.

Said intermediate spring 60 is of sufficient strength that when it is put under tension by the resistance of the springs 63 and 64 as it approaches the dead center position, the reaction is sufficient not only to frictionally hold the coin until the dead center position is reached, but also to suddenly thrust the member 62 onward after the springs 63 and 64 have passed the dead center point; and the moment the springs 63 and 64 have passed the dead center point, they operate to instantly turn the revolvable member 62 to normal or initial position where it comes to rest and is held in such initial position by the springs 63 and 64.

The spring 60 is so tensioned at the point at which the springs 63 and 64 hold the member 62 at rest that tappet 38 will be just in front of the coin seat 43, so that whenever a coin is in the seat 43 and the crank is turned, the coin in the coin seat 43 will contact the tappet 38 and act to revolve it as before and cause the tappet 38 to turn the member 62 until the springs 63 and 64 pass the dead center, thereupon suddenly completing the revolution of shaft 58 by spring action. When the member 62 is thus at rest, the friction on the coin due to crank action and resistance of the tappet 38 to the advance of the coin, is relieved, thus allowing the spring 45 to whirl the carrier 33 round in reverse direction and cause the tappet 38 to positively kick the released coin out of the coin seat 43 in the carrier 33, which in that position of the crank is inverted, so that the coin is positively thrown out of such seat into a coin receptacle.

The springs 63 and 64 secured to the pin 65 on the member 62 and to the frame, yieldingly hold the said member 62 and its connections at the rest position, and it not only operates the tappet 38 to eject the coin, but also operates to completely dispense a cup.

The crank 30 is only oscillatable and stops short of a complete revolution, as indicated in Fig. 1, and the gears 47, 48 and 57 are so arranged that the member 62 can be turned to a point somewhat more than 180 degrees from rest by operation of said crank and before the crank reaches the limit of its movement, the springs 63 and 64 completing the revolution of the member 62 and the tappet 38 automatically returning to rest position and completing the cup vending cycle of operation.

Means are provided to prevent the insertion of a coin when the supply of cups is exhausted, and such means comprises a spring-actuated coin-stop operating arm 66, best shown in Figs. 8, 10 and 11, that is pivoted intermediate its ends at 67, 145 is provided at one end with a finger 68 constructed and arranged to be pressed against the rim of a supported cup by means of a spring 69 secured to the frame 20 by means of the screw 70. The coin-stop operating arm 66 is extended beyond 150

the pivot 67 and is provided with the pin 71 adapted to be inserted into and across the coin slot 37 to prevent the insertion of a coin into the slot and stop it in a position whereby the purchaser may regain the coin without its passing into the machine when there are no wares available to be purchased.

In this way, when the last cup is disposed from the stock so that it is removed from contacting position with finger 68 the coin-stop operating arm 66 is operated under tension of the spring 69 to move the pin 71 into the coin slot 37 and prevent the insertion of a coin by an intending purchaser.

15 The friction of the finger 68 on the rims of the cups would prevent the cups from moving down, and it is necessary to withdraw the finger from the cups during the operation of dispensing the cup; this is effected by means of the operation of 20 a cam-actuated pin 72, best shown in Figs. 8, 10, 11 and 17; this pin 72 enters the coin slot 37 from the side opposite to the recited pin 71 and is normally retracted by a spring 73 to hold it out of the coin slot 37; it is operated by means 25 of a rocking arm 74 pivoted at 75 to the frame 20 and is actuated by means of engagement at one end by the cam 76 which is secured to the recited crank shaft 31 which oscillates with the handle 30; therefore, upon operation of the handle 30, 30 the cam acts to insert the pin 72 into and across the coin slot 37, and is provided with sufficient travel to engage and move the pin 71, and thru it move the finger 68 out of engagement with a cup in the cup dispensing device. When the pin 72 35 has been moved into engagement with the pin 71, it has passed transversely thru the coin slot 37 so that another coin cannot be inserted in said slot, and further provides a means for requiring the handle 30 to be in initial position when a coin 40 is inserted in the coin slot 37, thereby assuring correct positioning of the coin carrier 33 relative to the slot 37 when the coin is inserted.

The cam 76 extends around the axis of the shaft 38 sufficiently to hold the arm 74 and the pin 72 in operating position during an oscillation of the crank, whereby the pin 72 is contacting the pin 71 and retracting the finger 68 throughout all except a limited initial arc of the crank oscillation, so that while the cup dispensing elements are lowering a cup, the finger 68 is held retracted from the projecting cup rim, but when the crank 30 is returned to its initial position, shown in solid lines in Figs. 1 and 11, the spring 69 again presses the finger 68 against a cup, which 55 limits the movement of the arm 66 sufficiently that the pin 71 does not enter the coin slot 37; when there is no cup present to contact the finger 68, the absence of a cup permits the finger 68 to move a sufficient distance to rock the arm 66 and thus move the pin 71 into and across the coin slot 37, thus providing a slot closing stop to prevent coins from being inserted into the coin slot 37.

60 The just described operation of providing a slot closer wherein is utilized the combination of the two pins 71 and 72, operates to provide a permanent stopping means at all times when there are no cups in the machine to vend the drinks with, as the absence of the cups allows the pin 71 to enter the coin slot 37, and should the crank 30 be oscillated the cam 76 operates to move the pin 72 into and across the slot 37 where it contacts and moves the pin 71, but upon its return movement the pin 71 follows the pin 72 and again is

positioned across the slot 37, thus effectively preventing the passage of a coin therethru.

In view of the fact that the drink dispensing device herein illustrated is fully and completely described in detail in my recited co-pending application, filed October 26, 1925, Serial No. 64,735, of which this is a division, I will include but a brief description herein for the purpose only of illustrating a device with which the invention herein disclosed of a coin-controlled mechanism may be associated.

80 The drink dispensing mechanism is contained and supported by elements associated with the recited frames 20 and 21 and consists of a hollow casting 77 having a cover plate 78. A fountain tray 79, see Fig. 2, has a fountain or jar 80 inverted thereon. A tube 81 leads from the tray 79, being secured to the casting 77 by screws threaded into flanges 82. Said tube opens into an intake chamber 83, which, in turn, opens into a measuring or pump cylinder chamber 84. Said chamber 84 communicates with outlet chamber 85 thru a duct 86, best shown in Fig. 7. Said chamber 85 has an outlet 87 that alines with a tube 88. A vent 89 at the top of chamber 85 95 admits air to prevent siphoning of liquid from the jar 80.

A rod 90 having a valve 91 thereon extends thru the casting 77 and has at its lower end an anti-friction roller 92 that rests on a cam 105 face 93 formed on the periphery of the recited revolvable member 62 and is raised and lowered thereby. Said cam causes the valve 91 to temporarily close the passage 94, which leads from the bottom of a pressure and float chamber 95 into the expansion chamber 96. Near the top of its upward stroke and after the valve 91 is seated, and the cam 93 is moving during the spring retracting portion of the revolution of the member 62, the rod 90 lifts a valve stem 113 97, having a spring 98 therearound, and unseats a pressure liquid inlet valve 99, thus permitting the pressure fluid to flow from the pipe 100 thru the cage 101 and thence into the chamber 95 while the outlet 94 is closed by valve 91.

100 A pressure tank 102, best shown in Fig. 6, is connected to the recited pipe 100 and has a shut-off valve 103. During the time that the inlet valve 99 is open and the outlet valve 91 is closed, the float valve stem 104 in chamber 95, see Fig. 125 7, is lifted by means of a float 105 attached thereto until said float, by means of a valve 106, closes a vent 107 in the cover plate 78; the said vent 107 communicates with the outer air to allow free escape of gas until the float 105 and the vent valve 106 are lifted.

110 Pressure chamber 95 communicates thru a port 108 with the recited pump cylinder chamber 84 having a piston 109 attached to piston rod 110 and at a spaced interval below the piston 109 and attached to the rod 110 is a second piston 111 for the purpose of measuring and pumping the syrup.

115 The expansion chamber 96 is provided with outlet tube 112 which extends to a point above and adjacent to the edge of a cup positioned on the U-shaped lip 25 that the liquid may pass thru the outlet 112 and be poured into a positioned cup; the tube 112 is so steeply aslant that the liquids discharged thereto will flow out of the spout section with sufficient velocity to shoot over into the positioned cup, but the spout terminates sufficiently behind the front rim of the drip cup 113 to allow any drops which may drip from the end of the spout to drain out thru the

recited drain 27 without smearing the lip 25 or the rim of the cup 26.

The cup dispensing device comprises a magazine 114 mounted on and stationary to the upper frame 21, and has a circular cup-way 115 above and axially aligned with the passage 24 having a chamfered internal flange ring 116 below which thin mutilated worm-rimmed or peripherally threaded revoluble cup-feeding disks 117 are arranged to support a stack of nested cups 118 in the magazine 114. Two of said disks are mounted on shafts 119 revolvably mounted in the upper casing 21 while the third disk is mounted on the upper end of the shaft 56, the lower end of which has mounted on it the recited gear wheel 51, the shaft 56 has further secured to it the spur gear 120 which contacts and drives an annular gear 122 which engages and drives additional spur gear wheels 123 mounted on each of the shafts 119. The disks 117 are arranged with their spiral peripheries projecting into the cup-way 115 to unitedly support the rim of the lowermost cup at one part of the revolution and the spiral peripheral grooves in said disks are adapted to receive the rim of the lowermost cup and move such rim down and thus cause the cup to drop into the vertical passage 24 when the disks are turned to the appropriate position for supporting the next cup rim.

Preferably there are three of such disks symmetrically disposed, as shown, and in fixed relation to respective operating gears.

The source of power to operate the cup dispensing mechanism is the crank 30 and thru the various recited connections to the shaft 56 which has secured to it the recited spur gear 120 and also one of the disks 117, the spur gear 120 drives the annular gear 122 thru an idle gear 121, the annular gear 122 meshes with the other spur gears 120 on the recited shafts 119 to which are secured the other two disks 117 and the rotation of the annular grooves in the periphery of the disks is so timed that a cup will be dropped onto the lip 25 in time to receive the mixed drink as it is discharged thru the outlet 112. As recited, the same movement of the crank 30 oscillates the cam 76 which actuates the pin 72 to enter the coin slot 37 and contact and operate pin 71 to rock the arm 66 and thus remove the finger 68 from contact with the cup then residing in the ring 116 at the time that the operation is commenced, thus removing any friction which might be caused by the contact of the finger 68 with the cup present in the ring 116.

As recited, the oscillation of the crank 30, assuming there is a coin in the coin carrier 33 to complete connection between the crank and the driven elements of the machine, brings the connected mechanism to the point where the springs 63 and 64 pass dead center and the action of the spring 60 completes the revolution of the shaft 35 with a quick jerking movement; advantage is taken of this accelerated movement to complete the separation of the lowermost cup from the stack of cups and force it downward with an accelerated movement at the instant of separation of it from the stack; this accelerated movement or rotation of the disks 117 brings the supporting part of the edge of the disk under the flange or rim of the next cup in the stack as it drops down during the removal of the first cup, thus providing a continuous support for the stack of cups, and further the accelerating movement of the disks 117 at the separation point insures

a thorough and efficient breaking away of the lowermost cup from the stack, thus preventing the sticking of the lower cup to the next cup above from its having been pressed into a stack by continuous confinement therewith.

For the purpose of checking the monetary receipts of the device in the form of the coins deposited in the coin receiver against the number of drinks dispensed by the machine, I have provided a counter 124 of conventional form located adjacent the upper end of one of the shafts 119 which is provided with a pin 125 for the operation of the counter 124, thus recording one unit for each rotation of the shaft 119, which, having one of the disks 117 secured to it, will give a count of one for each cup that has been separated from the stack and used for dispensing a drink, therefore, the number of times that the machine is operated will be recorded.

Operation

Assuming that the drink vending device has been properly assembled, that there is provided a stack of cups in the magazine 114, and proper liquids provided for mixing a drink, that the operative mechanism is in original or starting position, that the crank 30 is in the position shown in Fig. 1 whereby the coin carrier 33 will be aligned with the coin slot 37 to receive a coin, and that the pins 71 and 72 are withdrawn from the coin slot 37, the machine is now in proper assembly to be operated.

To operate the machine, a coin of the required denomination is placed in the slot 37 and runs down into the grooves 42 in the carrier 33 and seats in the coin seat 43, providing means for operatively connecting the shafts 31 and 35.

To operate the machine and thus complete the operative connection between the shafts 31 and 35, the crank 30 is turned in a clockwise direction, which oscillates the coin carrier 33, having a coin in the coin seat 43, and brings the coin into contact with the tappet 38, and as recited the tappet 38 is secured to the driven shaft 35, and thus upon the operation of the crank 30 the driven shaft 35 is caused to revolve, together with the gear wheel 47 secured to the opposite end of it. The gear train comprising the gears 47, 48, 51 and 54 are thereby rotated, as is also the gear wheel 57 which is secured to one end of the split shaft 58, connected by the coupling spring 60, to the rotatable element 62, and upon the actuation of this member, the springs 63 and 64 are also operated, as well as the cam 93 which controls the drink mixing and dispensing apparatus.

The cup dispensing apparatus is operated thru the actuation of the gear 56 by the recited gear train and the several connected gears operated thereby and drops the lowermost cup of the stack down onto the lip 25, thus positioning a cup to receive the mixed drink from the outlet 112. The rotation of the cam 93 actuates the valve mechanism controlled by the rod 90, and thereby measures and mixes a drink which is provided thru the outlet 112 and from that pours into the provided cup; the filled cup is now in position to be removed by the purchaser and consumed and the used cup may be dropped thru the aperture 28 for disposal.

The recited action of the springs 63 and 64 to complete the rotation of the member 62 also completes the rotation of the recited gear train connecting to the shaft 35 and to the cup dispensing mechanism, thus bringing them to the original

or starting position; at the same time the accelerated movement in the completion of the rotation releases the tappet 38 from its driven position relative to a coin in the carrier 33 and 5 throws it around so that it strikes the coin from the other side, and in view of the fact that the coin at this point of operation may drop from the inverted carrier 33 by gravity upon removal of the contact of the tappet 38, the tappet may be 10 able to move freely to complete its rotation, but should the coin not be dropped out of the carrier 33 by gravity the tappet striking at its edge is designed to knock the coin out of the carrier 33, whereupon it will drop into a coin receptacle, not 15 shown, and thus allow the carrier 33 to be reversed and oscillate back around to its original or starting position under tension of the recited spring 45; the spring 45, during the initial movement of the carrier 33, is tensioned by the rotation of one end of it, and under this tension it is 20 enabled to return the carrier 33 to its initial position, and consequently the attached shaft 31 and crank 30.

As above recited, the initial movement of the 25 crank 30 and shaft 31 have revolved the cam 76 a certain distance, and this movement has actuated the rocking arm 74 to insert the pin 72 into and thru the coin slot 37 to where it would engage the pin 71 and move it a sufficient distance to 30 rock the arm 66 and thereby remove the finger 68 from contact with the cup rim of the lowermost cup of the stack, which as it is resting at the ring 116 is in a position to be contacted by the finger 68; this removal of the finger 68 as recited prevents friction between it and a cup being 35 dispensed. The reversing of the carrier 33 which is keyed to the shaft 31 therefore reversely rotates the cam 76 and brings it back to its initial position wherein the rocker arm 74 will be removed 40 from pressure against the pin 72 and by action of the spring 73 it is removed from its position within the coin slot 37, the consequent contact with the pin 71 thus leaving the coin slot 37 free for the passage of a coin, in so far as the operation 45 of the pin 72 is concerned; the pin 72 has acted in two capacities during this operation, one as an actuator for the pin 71, and the second being as a slot closer during the period it resided within the coin slot 37, thus preventing a coin 50 being inserted into the coin slot while the machine was being operated for drink dispensing purposes.

For further operation of certain elements of the machine, it is now assumed that the supply 55 of cups in the magazine 114 has been exhausted and therefore, there being no cup resting at the ring 116, the finger 68 under tension of the spring 69 will have traveled inwardly into the area normally occupied by a cup, and this movement will 60 rock the arm 66, thus positioning the pin 71 within and across the coin slot 37, thereby providing a positive slot closer preventing the insertion of a coin into the coin slot 37 far enough but that the 65 intending purchaser may retain a hold upon the coin, and thus the coin will not pass into the machine when there are no wares to be vended. The crank 30 may be oscillated at any time whether there be wares in the machine to be vended or not, but unless a coin has been dropped into the 70 slot 37 and is properly positioned in the carrier 33, the moving of the crank 30 will have no effect upon the other mechanism in the machine except to operate the rocking arm 74 which forces the pin 72 into and across the coin slot 37, and should 75 there be no cups in the machine the pin 71 is

normally residing across the slot 37 and the operation of inserting the pin 72 will only contact the end of the pin 71 and force it back across the slot 37 and the slot 37 will continue to be closed, because the pin 72 will be forced into the position occupied by the pin 71 and upon its return the pin 71 will return across and close the slot 37, thereby, coins will be prevented from being inserted by the combined action of the two pins 71 and 72, which, when the supply of wares in the machine is exhausted, combine to act as a permanent slot closer until the supply of cups is replenished in the machine.

The beverage delivery mechanism is timed to operate during that portion of the movement of crank 30 which follows the delivery of a cup to the position to be filled. As this mechanism, separately considered, is described and claimed in my original application and forms no part of this present application, a more detailed description of its action is omitted from this specification.

The cup delivery mechanism as such is timed to deliver a cup during the first portion of the operation of the crank 30, and as this mechanism, separately considered, is described and claimed in a co-pending divisional application, forms no part of the present application, a more detailed description of its action is omitted from this specification.

I claim:

1. In a liquid dispensing machine having a pressure chamber provided with an inlet and an outlet; valves for controlling the flow of effervescent liquid into and from said chamber; a cam to operate said valves; a spring to hold the cam in a predetermined position with the inlet valve closed and the outlet valve open; said spring being arranged to snap past the dead-center to bring the cam wheel to non-operative position; a crank; a coin carrier connected to the crank; a tappet; said coin carrier adapted to receive an element frictionally held in place to operate the tappet when the crank is turned; a spring adapted to be placed under tension by the crank operating through the frictionally held element to apply tension to the cam retracting spring; said tappet being operated by the cam retracting spring to move the frictionally held element out of place when the cam retracting spring is moved past dead-center; and a spring to return the crank to 115 normal position.

2. In a coin operated machine; a coin carrier provided with a slot to receive a coin; means to oscillate the coin carrier; a lug adapted to be actuated by a coin in the coin carrier; a spring 130 adapted to be given tension by the operation of the lug and adapted to rotate the lug to the initial position; and a tappet rotatable by the spring to dislodge the coin upon such return.

3. The combination with a valve adapted and arranged to control discharge of a liquid under pressure; of a revolvable member to close the valve; a spring eccentrically connected to said revolvable member and adapted and arranged to be put under tension during a valve closing portion of the revolution of said member, and to continue the revolution of said member after the spring passes the dead-center; an intermediate spring to revolve the revolvable member; and coin actuated means to give tension to the intermediate spring for the purpose of revolving the revolvable member to give tension to the eccentric spring; the tension of the intermediate spring serving to hold the coin in operative position, until 145 150

the eccentrically connected spring passes dead-center.

4. In a vending machine, a body having a coin slot therein; a shaft adjacent said slot; means 5 journalling said shaft; a hand crank on said shaft; a coin carrier fixed on said shaft and having a slot adapted to receive a coin from the coin slot; a lug adapted to be engaged by the coin carried by said carrier; vending means; means operatively connecting said lug and said vending means; a pin adjacent said slot; a lever pivoted adjacent to and engaging said pin, and arranged to be operated by the crank to operate said pin to bar said coin slot while the crank is operated; 10 and means to remove said pin from barring said coin slot when said crank is in normal inoperative position.

5. A coin carrier adapted to hold a coin; means for oscillating the coin carrier; a lug adapted 20 to be oscillated by the coin of said coin carrier; a spring to return the lug to initial position; a tappet adapted to dislodge the coin from the coin

carrier; a revolvable member; a spring eccentrically connected to the revolvable member and adapted and arranged to be put under tension during a portion of the revolution of said member and adapted to operate the member to rotate the same to initial position; and a spring connecting the lug and tappet to the revolvable member.

6. In a device as disclosed adapted to be associated with ware vending mechanism and including coin receiving and conveying elements; operating means for said conveying elements; slot closers for said receiving element wherein one slot closer is operated by the said operating means to close the receiving element during a vending operation; a second slot closer adapted to automatically close said receiving element during the absence of wares in the said vending mechanism; means whereby the first mentioned slot closer when in slot closing position acts to remove the second mentioned slot closer from contact with wares while being vended.
